UNITED STATES PATENT OFFICE.

CHARLES B. FRALEY, OF CHICAGO, ILLINOIS, ASSIGNOR TO HAGGARD & MARCUSSON COMPANY, OF CHICAGO, ILLINOIS, A CORPORATION OF ILLINOIS.

BED-BOTTOM FABRIC.

No. 872,995.

Specification of Letters Patent.

Patented Dec. 3, 1907.

Application filed February 11, 1907. Serial No. 356,801.

To all whom it may concern:

Be it known that CHARLES B. FRALEY, citizen of the United States, residing at Chicago, in the county of Cook and State of Illinois, has invented certain new and useful Improvements in Bed-Bottom Fabrics, of which the following is a specification.

This invention relates to elastic bed-bottom fabrics of the diamond type, and is principally composed of reticulated material made up of a number of wire units; and has for its principal object to provide a structure of this character that is simple and economical in manufacture and very efficient in practical use. The commercial success of this class of wire spring fabrics greatly depends on the facility with which the unit parts can be formed and assembled from the constituent elements entering into the structure and the convenience with which it may be attached to the supporting-frame, as will be hereinafter set forth in detail.

The fabric is composed of a series of straight longitudinal wires or rods extending lengthwise of the frame and disposed at intervals across the width thereof, and a series of zigzag wires also running lengthwise and alternately looped around two contiguous units of the straight series and presenting a diagonal appearance and forming a diamond fabric.

In the drawing, Figure 1 is a plan of a bed bottom embodying the improved features. Fig. 2 is a detail of the end and intermediate connections of the wire units; and Fig. 3 is a detail showing the assembled relation of one of the zigzag units and the longitudinal fabric wires.

A may represent the companion side rails and B the end rails which form the usual supporting frame to which the bed-bottom fabric is attached. In this instance the elastic fabric consists of a number of straight longitudinal wires or rods 4 and a series of zigzag wires 5 and 6 interwoven therewith and running the full length thereof, as shown in Fig. 1.

The reference numeral 4 indicates the longitudinal wires, and the numerals 5 and 6 indicate the zigzag wires and refer to the same as the whole number, but other numerals will be used in specifically referring to individual parts for the purpose of making the construction features clear. The longitudinal

wires 4 are provided at their respective ends 55 with loops or eyes 7 which in their turn engage the inner loop ends 8 of a series of helical tension springs 9 connected to the loop ends 7 of each alternate straight longitudinal wire 4. The outside ends 10 of the springs 9 60 are secured in the respective end rails.

One end of the outside diagonal wire 5 connects with the upper loop end 7 of the outside longitudinal wire 11, of the series 4. From this upper loop end the wire 5 runs 65 inward diagonally with a half interlock turn 13 around the next straight wire 14, of the series 4, and then outward diagonally with a half interlock turn 15 around the outside wire 11, and so on alternately until the opposite or lower end is reached when the terminal end of the zigzag wire 5 is secured in the loop end 7 of the outside straight wire 11. The next zigzag wire 6 starts from the upper loop end 7 of the third straight wire 4, the 75 first diagonal section thereof running outward with an interlock or half loop turn 16 around the straight wire 4, then diagonally back to and with a half turn 17 around the third wire 4 from the edge, and so on back 80 and forth until the end of zigzag wire 6 is secured in the loop end 7 of the third straight wire 4. This description of the interweaving features of two companion zigzag wires will apply to all alike throughout the structure 85 in forming the diamond design shown.

It will be noted by reference to Fig. 2, that the zigzag wires extend around the longitudinal wires from opposite directions in maintaining a symmetrical shape. It will 90 further be seen that the zig-zag wires in looping about the wires 4 do not interlock with each other, the loops being entirely independent of each other. By this arrangement the junction of the longitudinal 95 and zigzag wires is movable instead of fixed so that the zigzag wires have a free sliding movement on the longitudinal wires in conforming to any change when subjected to a load or pressure whether equally distributed 100 over the surface or not. When the weight or pressure is removed the parts quickly assume their normal position.

The parts may be assembled with the greatest facility, which advantage is an important factor in the cost of production.

Having thus described my invention, what I claim is—

A bed bottom fabric, composed of a number of spaced straight longitudinal wires, of a series of zig-zag wires, each extending back and forth diagonally between two adjacent straight wires and looping loosely thereabout at the angles, each pair of zig-zag wires forming a diamond mesh, and the looped portions of each pair of wires which interlock with the same region on a longi-

tudinal wire being entirely independent and capable of individual movement.

In testimony whereof I have signed my name to this specification in the presence of two subscribing witnesses.

CHARLES B. FRALEY.
